FUEL COMBUSTION

Gustaf Dalén, Lidingo, Sweden, assignor to
Svenska Aktiebolaget Gasaccumulator, Stockholm, Sweden, a corporation of Sweden

Application October 30, 1933, Serial No. 695,882
In Sweden November 3, 1932

19 Claims. (Cl. 158—53)

The present invention relates to combustion and has particular reference to the combustion of liquid hydrocarbon fuels. Still more particularly, the invention relates to the combustion of heavy hydrocarbons, such, for example, as what is commonly termed fuel oil.

In one of its phases, the invention relates to cook-stoves, particularly stoves of the type adapted to be continuously maintained at elevated temperature. The invention, however, is not limited to such apparatus, but may also be applied to other heat consuming devices, such as water heaters, refrigeration apparatus of the absorption type requiring heat for operation, and other devices having like heat requirements.

The general object of the invention is to provide for reliable continuous operation of combustion apparatus in which heavy hydrocarbon fuel is vaporized to provide the fuel vapor necessary for combustion. Other and more detailed objects and the nature and advantages of the invention will appear more fully in the following specification, in which the invention is described in its application to a domestic cook-stove. In the drawings forming a part of the specification:

Fig. 1 is a vertical section of a domestic cook-stove taken on the line 1—1 of Fig. 5, including apparatus embodying the invention;

Fig. 2 is a similar section on an enlarged scale showing part of the apparatus illustrated in Fig. 1;

Fig. 3 is a section taken on the line 3—3 of Fig. 2;

Fig. 4 is a section taken on the line 4—4 of Fig. 2;

Fig. 5 is a section on an enlarged scale taken on the line 5—5 of Figs. 1 and 2; and

Fig. 6 is a view taken on line 6—6 of Fig. 2.

Referring now to Figs. 1 and 2, the stove indicated generally at 10 is of the type adapted to be continuously maintained at elevated temperature and comprises a relatively heavy metal structure indicated generally at 10 providing hot plates 12 and 14 and an oven 16. A second low temperature oven 18 may also be provided. The hot plates 12 and 14 and also oven 16 are adapted to be heated by conduction of heat through the metal from gases of combustion which pass through channel 20 to a suitable stack opening 22 adapted to be connected to the chimney. The metal structure 10 is adapted to accumulate heat and is surrounded by suitable insulating material, such as asbestos or kieselguhr, indicated at 24, and the hot plates 12 and 14 are covered when not in use by insulated cover plates 26 and 28.

The hot combustion gases for heating the structure 10 are provided by a burner indicated generally at 30 and adapted to burn a gaseous fuel mixture comprising air and hydrocarbon fuel vapor. Air for combustion is supplied to burner 30 through the passage 32 which is in communication with the surrounding atmosphere through the opening 34. Around the base of the burner 30 there is provided a metal mass 36 having two vaporizing chambers 38 and 40 therein (see Figs. 3 and 4). Chambers 38 and 40 are each in communication with the lower portion of the burner 30 by way of passage 42 with which the upper portions of the vaporizing chambers are in communication by way of ports 44 and 46. Chamber 38 has associated therewith a liquid fuel feeding member 48, the lower portion of which provides a central fuel feeding tip 50 from which liquid fuel is adapted to fall onto a vaporizing surface 52, which in this instance is provided by the bottom wall of the vaporizing chamber. The vaporizing chamber and the lower part of the fuel feeding member are connected by means of a pipe 54 and an annular space 56 communicating with pipe 54 surrounds the fuel feeding tip 50 of the member 48. Chamber 40 has associated therewith a like fuel feeding member 58 having a fuel feeding tip 60 adapted to cause fuel to fall onto the vaporizing surface 62. Chamber 40 and member 58 are connected by pipe 64, and tip 60 is surrounded by annular space 66.

Fuel is supplied alternatively to one or the other of the fuel feeding members by apparatus which will now be described. Liquid hydrocarbon fuel is fed, preferably by gravity, from a suitable reservoir (not shown) through the supply line 68 (Fig. 5) through a strainer 70 in a chamber 72, from which it flows through the passage 74 to a float chamber 76 in which the level of fluid is maintained substantially constant by the float 78, which operates to control flow of fuel through the passage 74. From the float chamber 76 fuel flows through the pipe 80, the labyrinth 82 and pipe 84 to a feeding orifice 86 controlled by a needle valve 88. The orifice 86 is positioned above a cup-shaped receptacle 90 in which is pivotally mounted a plate 92 adapted to direct fuel either to the outlet passage 94 leading from chamber 98 in receptacle 90, or to the outlet passage 96 leading from chamber 100 therein. Chambers 98 and 100 are separated by the web 102. Passages 94 and 96 communicate respectively with the fuel feeding members 58 and 48, the connection between passage 94 and fuel feeding member 58 being shown in Fig. 2.

and comprising an inclined conduit 104. The fuel feeding members 48 and 58 and the receptacle 90 are preferably formed by a single integral casting, as shown in Fig. 2, through which the several fuel feeding passages are bored.

The annular spaces 56 and 66 surrounding the tips of each of the fuel feeding members are placed in communication with the surrounding atmosphere to permit a restricted amount of air to be admitted at these places for a purpose to be explained later. In Fig. 2 the connection for this air supply to the fuel feeding member 58 is shown at 106.

The lower part of the passage 42 is preferably provided with an overflow pipe indicated at 108, the outer end of this pipe terminating in a passage or discharge opening 110 (Fig. 5), beneath which there is advantageously suspended an overflow receptacle 112. Receptacle 112 is suspended from a bar 114, to which is attached stem 116 of the needle valve 88, and, as will be evident from Fig. 5, flow of fuel through the orifice 86 will be shut off in the event liquid fuel overflows into the receptacle 112. The metal bar or strip 114 is supported intermediate its ends by the pivot 118 and the end of the strip opposite the end to which the needle valve stem is secured is fastened to one end of a hollow curved expansion element 120 of the Bourdon tube type, the other end of which is secured, as at 122, to one arm of a lever 124 pivoted at 126. The expansion element 120 is in communication with a thermostat tube 128 leading from a thermostat (not shown) and adapted to reflect the temperature of the structure 10. Tube 128 and the element 120 are adapted to be filled with any suitable expansible thermostat fluid. The fixed point of the expansible element 120 is determined by the position of lever 124, which is biased by a spring 130, working against any suitable fixed abutment 132, toward an adjustable cam 134 adapted to be rotated to determine the position of adjustment of the lever.

The position of the plate 92 for directing fuel either to passage 94 or to passage 96 is controlled by means of an arm 136 projecting upwardly from the plate and at its upper end engaging the bifurcated lower end 138 of a lever 140 pivoted at 142. The upper arm of lever 140 is bent so as to project through an arcuate slot 144 in the outer casing 146 of the stove, and terminates in an indicator arm 148 having an actuating handle 150. The outer casing 146 of the stove preferably has marked thereon the scale or index 1-15, 15-1, as indicated in Fig. 6.

The metal mass 36 is preferably enclosed in insulating material indicated at 152, and air passing to the air supply pipe 32 of the burner also advantageously circulates in the space 154 around the insulation 152 and also around the fuel feeding members and the parts providing the channels for supplying fuel and air to these members.

While the form of fuel burner employed constitutes per se no part of the present invention, the burner arrangement shown herein by way of example, which forms the claimed subject matter of my copending application Serial No. 695,883, filed October 30, 1933, is of advantageous form. In this burner arrangement the metal mass 36 provides a cup-shaped space with the bottom of which passage 42 is in communication, and in the center of which there is disposed the perforated burner pipe 156. A second and larger perforated burner pipe 158, the lower end of which is above the lower end of pipe 156, surrounds pipe 156 to provide between the two pipes an annular

space 160. A third pipe 162, larger in diameter than pipe 158 and imperforate, surrounds pipe 158. The lower end of pipe 162 is above the lower end of pipe 158. The space 160 between pipes 156 and 158 is in communication with the pipe 164, which serves to place the burner in communication with the combustion gas channel in the structure 10.

The operation is as follows:

Fuel vapor is burned in the space 160 by combustion air admitted thereto through perforated pipes 156 and 158, both of which pipes are in communication with the air space 154. The heat of combustion heats the mass 36 to high temperature, a high temperature of this mass being readily maintained because of the fact that the mass is well insulated, and by conduction through the metal the vaporizing surfaces 52 and 62 are maintained at very high temperature, for example, 900° F. or higher. Liquid fuel drops or falls through the orifice 86 onto the plate 92 and flows through the associated fuel conduit to one of the fuel feeding members. From the tip of the fuel feeding member the fuel falls onto the hot vaporizing surface and is substantially instantaneously vaporized. The vapor formed in the vaporizing chamber is drawn by the draft created by the burner through the passage 42 to the space between the two perforated burner pipes. Due to the suction created by the burner draft, air is drawn through the pipes (one of which is shown at 106 in Fig. 2) to the spaces around the fuel feeding tips 50 and 60 of the two fuel feeding members, this admission of air being continuous with respect to both of the fuel feeding members since both of the vaporizing chambers are in uninterrupted communication with the burner and therefore are continuously subject to draft from the burner whenever the burner is in operation. The quantity of air admitted around the fuel feeding orifice is restricted, being insufficient in amount to form a combustible gas mixture with the fuel vapors being formed in the vaporizing chamber to which fuel is being admitted. As will be evident, the air admitted through a pipe such as pipe 106 will be relatively cool as compared with the temperature of the mass 36 and the parts associated therewith, and the purpose of this air supply is to enshroud the falling fuel so as to prevent premature vaporization thereof. By so enshrouding the falling fuel and conducting it to the fuel feeding member through passages which are relatively cool, the formation of carbon deposits at or adjacent to the fuel feeding member due either to premature vaporization or recondensation of fuel vapors on the wall surfaces is materially retarded if not entirely eliminated, and the formation of a carbonaceous deposit of a coke-like nature on the vaporizing surfaces is also retarded because of the fact that the oxygen content of the restricted quantity of air, while insufficient to form a combustible gas mixture in the vaporizing chamber, will tend to burn away such carbonaceous deposit as it forms. Due to the introduction of this restricted air supply to the vaporizing chamber, the accumulation of carbonaceous deposits of fuel residue in the chamber is very slow, but in time sufficient accumulation may occur to adversely affect the efficient operation of the vaporizer, particularly when a substantial accumulation of residue or coke forms on the vaporizing surface.

In order to permit the continuous operation of the burner for long periods without interruption, and also in order to effect removal of carbonace-

ous accumulations from the vaporizers, a plurality of vaporizers is provided and after one vaporizer has been in operation for a period of time, which experience has indicated will result in the accumulation of an undesirable amount of residue in the vaporizing chamber, the supply of fuel to such vaporizer is cut off, and fuel is directed to another vaporizing chamber. It will be evident that in a construction such as that disclosed, fuel vapor will be substantially immediately formed in the vaporizing chamber to which fuel has been directed, so that there will be no interruption in the supply of fuel vapor to the burner. Even if there were sufficient interruption in the supply of fuel vapor to cause the burner flame to be extinguished, the entire apparatus is at such high temperature that ignition would automatically occur immediately upon the resumption of the supplying of fuel vapor. The restricted supply of air admitted to the vaporizing chamber from which fuel has been cut off continues to flow through this chamber under the influence of the burner draft, and because of the fact that the vaporizing chamber is continuously maintained at very high temperature, the oxygen in the air continuing to flow to the vaporizing chamber combines with the carbonaceous residue therein and gradually burns away the deposits in the chamber while another vaporizing chamber is in operation.

With a fuel vaporizing arrangement of the kind shown, the formation of carbonaceous deposits in the vaporizing chambers is so slow that continuous operation of the burner may readily be effected with but two vaporizing chambers adapted to be operated in alternation. Experience has shown that where the apparatus is utilized in connection with the heating of a cook-stove of the type illustrated, vaporization of the required amount of fuel may be effected continuously by a single vaporizer for a period of about a month, but it is preferable to change operation of the vaporizers somewhat more frequently, and in order to insure the shifting of operation of the vaporizers at proper intervals, the index indicated in Fig. 6 is advantageously employed in conjunction with the shifting lever 148. This index is advantageously marked 1-15 and 15-1, the figures representing the days of a month, it being intended that the shifting lever 148 be in the position shown in Fig. 6 during the period from the first to the fifteenth day of a given month, and in the opposite position during the period from the fifteenth of a given month to the first of the succeeding month.

In the embodiment of the invention hereinbefore described by way of illustration, air is employed as the enshrouding fluid for the fuel falling onto the vaporizing surfaces, but it will be evident that other oxygen containing fluids may be employed in accordance with the invention. The essential characteristic is that the enshrouding fluid contain oxygen which is admitted to the vaporizing chambers at a rate such that the enshrouding fluid is essentially inactive to produce a combustible gas mixture in the vaporizing chambers, and is active only to the extent of effecting the burning away of carbonaceous deposits in these chambers.

It will be evident that the invention is not restricted to the use of but two vaporizers, since a larger number of vaporizers, to which fuel is alternatively supplied, may be used, and it will further be evident that many changes and variations in the specific structure employed may be

resorted to without departing from the spirit and scope of the invention as defined in the appended claims, which are to be construed as broadly as is consistent with the state of the prior art.

What I claim is:

1. Liquid fuel combustion apparatus comprising a burner, a plurality of vaporizers each including a fuel vaporizing surface and a fuel feeding member for causing liquid fuel to fall on said surface, means for conducting fuel vapors from said vaporizers to said burner, means for continuously admitting a gaseous combustion supporting medium to said burner, means for continuously admitting a relatively restricted supply of gaseous combustion supporting medium to each of said vaporizers, and means for supplying liquid fuel alternatively to different of said fuel feeding members. 5

2. Liquid fuel combustion apparatus comprising a burner, a plurality of vaporizers in heat receiving relation with respect to said burner, each of said vaporizers including a main vaporizing chamber, a vaporizing surface in said chamber continuously heated by heat from said burner and a fuel feeding member for causing fuel to fall 10 on said vaporizing surface, passages providing constant communication between said chambers and said burner, means for continuously admitting a gaseous combustion supporting medium to said burner, means for continuously admitting to 15 each of said vaporizing chambers a quantity of gaseous combustion supporting medium insufficient to form a combustible gas mixture with the fuel vapors therein, but sufficient to burn away 20 hot carbonaceous residue from the vaporizing 25 surfaces, and means for supplying liquid hydrocarbon fuel alternatively to different of said fuel feeding members. 30

3. Liquid fuel combustion apparatus for combustion with natural draft comprising a burner 40 for continuously burning a combustible gas mixture, a metal mass disposed in heat receiving relation with said burner and having a plurality of vaporizing chambers therein, fuel feeding members for causing liquid fuel to fall into each 45 of said chambers to be vaporized by contact with a hot vaporizing surface therein, passages for conducting vaporized fuel to said burner, means for continuously admitting to each of said vaporizing chambers a quantity of air insufficient to 50 form a combustible gas mixture with the fuel vapors in said chambers but sufficient to burn away hot carbonaceous residue from the vaporizing 55 surfaces, and means for supplying liquid hydrocarbon fuel alternatively to different of said fuel feeding members. 55

4. Liquid fuel vaporizing apparatus for supplying vaporized hydrocarbon fuel comprising structure providing a plurality of vaporizing chambers each having a high temperature vaporizing surface for vaporizing liquid hydrocarbon fuel, fuel feeding members for causing liquid fuel to fall on said vaporizing surfaces, passages for conducting fuel vapor from said chambers, said passages being open to permit uninterrupted flow 60 of gaseous fluid from said chambers, means for uninterruptedly admitting restricted quantities of air to said chambers, and means for alternatively supplying liquid hydrocarbon fuel to different of said fuel feeding members. 65

5. Liquid fuel vaporizing apparatus for supplying vaporized hydrocarbon fuel comprising a mass for storing heat, a plurality of vaporizers associated with said mass, each of said vaporizers including a vaporizing chamber, a vaporizing sur- 70 75

face maintained at a temperature sufficient to vaporize liquid hydrocarbon fuel by conduction of heat through said mass and a fuel feeding member for causing liquid fuel to fall on said vaporizing surface, passages for continuous withdrawal of gaseous fluid from said vaporizing chambers, means for uninterruptedly admitting restricted quantities of air to said chambers, and means for alternatively supplying liquid fuel to different of said fuel feeding members.

6. Liquid fuel vaporizing apparatus for supplying vaporized hydrocarbon fuel comprising a metal mass heated by a burner and providing a plurality of vaporizing chambers each having a vaporizing surface heated by conduction of heat from the burner through the mass to a degree sufficient to vaporize liquid hydrocarbon fuel, fuel feeding members for causing liquid fuel to fall on said vaporizing surfaces, passages for uninterrupted withdrawal of gaseous fluid from said vaporizing chambers due to draft created by the burner, means for uninterruptedly admitting restricted quantities of air to said vaporizing chambers and means for alternatively supplying fuel to different of said fuel feeding members.

7. Liquid fuel combustion apparatus comprising a burner for burning a gaseous fuel mixture with natural draft, a metal mass in heat receiving relation with said burner and providing a plurality of vaporizing chambers each having a vaporizing surface heated by conduction of heat from said burner through the mass to a degree sufficient to vaporize liquid hydrocarbon fuel, fuel feeding members for causing liquid fuel to fall on said vaporizing surfaces, passages for uninterrupted withdrawal of gaseous fluid from said chambers to said burner due to the draft created by combustion in the burner, whereby to supply the burner with fuel vapor for continuous operation, means for admitting quantities of air to the vaporizing chambers insufficient to form a combustible gas mixture with the vaporized fuel therein but sufficient to burn away carbonaceous residue from said vaporizing surfaces, and means for supplying liquid hydrocarbon fuel alternatively to different of said fuel feeding members.

8. Liquid fuel combustion apparatus comprising a burner for burning a gaseous fuel mixture, liquid fuel vaporizing apparatus comprising two vaporizers each including a vaporizing chamber, a vaporizing surface heated by heat from said burner to a temperature sufficient to vaporize liquid hydrocarbon fuel and a fuel feeding member for causing liquid fuel to fall on said vaporizing surface, passages providing uninterrupted communication between said vaporizing chambers and said burner for supplying fuel vapor to the burner, means for uninterruptedly admitting a restricted quantity of air to each of said chambers whereby to retard by combustion the formation of solid carbonaceous deposits therein without forming a combustible gas mixture in the chamber with vaporized fuel therein, and means for alternatively supplying liquid hydrocarbon fuel to one or the other of said fuel feeding members.

9. Liquid fuel combustion apparatus comprising a burner for burning a gaseous fuel mixture, means for continuously supplying fuel vapor to the burner comprising a plurality of vaporizers each including a vaporizing chamber, a vaporizing surface heated by heat from the burner to a degree sufficient to vaporize liquid hydrocarbon fuel and a liquid fuel feeding member for causing liquid fuel to fall on said vaporizing surface,

passages for flow of gaseous fluid to said burner from said vaporizing chambers, means for uninterruptedly admitting restricted quantities of air to said chambers, and means for supplying liquid hydrocarbon fuel alternatively to different of said fuel feeding members comprising a fuel supply line, a separate fuel supply conduit for each of said fuel feeding members and means for directing fuel from said supply line to different of said supply conduits.

10. Liquid fuel combustion apparatus comprising a burner for burning a gaseous fuel mixture, means for continuously supplying fuel vapor to the burner comprising a plurality of vaporizers each including a vaporizing chamber, a vaporizing surface heated by heat from the burner to a degree sufficient to vaporize liquid hydrocarbon fuel and a liquid fuel feeding member for causing liquid fuel to fall on said vaporizing surface, passages for flow of gaseous fluid to said burner from said vaporizing chambers, means for uninterruptedly admitting restricted quantities of air to said chambers, and means for supplying liquid fuel alternatively to different of said fuel feeding members including a common supply line for supplying fuel by gravity, a separate supply conduit leading to each of said fuel feeding members, and switching means for directing fuel from said supply line into different of said supply conduits.

11. The method of producing heat by the aid of a burner and a plurality of liquid fuel vaporizers which comprises supplying heat continuously to the vaporizers from said burner, feeding fuel alternatively to different vaporizers and forming fuel vapor therein, withdrawing the fuel vapor thus formed due to draft created by the burner, and continuously drawing through the vaporizers a restricted quantity of air whereby to burn away the accumulation of carbonaceous fuel residue in an inactive vaporizer.

12. That improvement in the operation of a liquid fuel vaporizer adapted to supply hydrocarbon fuel vapor intermittently to a burner which consists in heating the vaporizer continuously to a temperature sufficient to vaporize liquid hydrocarbon fuel, causing liquid fuel to fall on a hot vaporizing surface in the vaporizer for a desired period of time, admitting a restricted quantity of air to the vaporizer while fuel is being vaporized therein, whereby to retard the accumulation of carbonaceous fuel residue on said vaporizing surface, and cutting off the supply of fuel to the vaporizer at the end of the desired period of time while continuing the admission of said restricted quantity of air and continuing the heating of the vaporizer after the supply of fuel to the vaporizer has been cut off, whereby to cause said air to burn away carbonaceous fuel residue from said vaporizing surface during the period when fuel is not admitted to the vaporizer.

13. Apparatus for continuously producing heat comprising a gaseous fuel burner, a plurality of liquid fuel vaporizers arranged to be continuously heated by heat from said burner, conduit means extending from said burner to said vaporizers to cause the draft created by the burner to continuously draw a restricted quantity of air through each of the vaporizers, means for feeding liquid fuel alternatively to different of said vaporizers to form fuel vapor therein for use in said burner, said conduit means including passages for flow to said burner of the fuel vapor formed in any active vaporizer to which fuel is supplied.

14. Apparatus for continuously producing heat

comprising a gaseous fuel burner, two liquid fuel vaporizers arranged to be continuously heated by heat from said burner, means for supplying liquid fuel alternately to one or the other of said vaporizers to be vaporized therein, conduit means extending from said burner to said vaporizers so that both of said vaporizers are continuously subjected to the influence of draft created by said burner and means for continuously admitting a restricted quantity of air to both of said vaporizers, whereby to cause said restricted quantity of air to retard the accumulation of carbonaceous fuel residue in the active vaporizer to which the fuel is being supplied and to burn away such residue in the inactive vaporizer to which fuel is not being supplied.

15. In liquid fuel burning apparatus, a gaseous fuel burner, a liquid fuel vaporizer having a vaporizing surface arranged to be continuously heated by heat from said burner to a temperature sufficient to vaporize liquid hydrocarbon fuel, means for causing liquid hydrocarbon fuel to fall on said vaporizing surface during intermittent spaced time intervals of desired duration to form fuel vapor in said vaporizer during such time intervals, and means for continuously admitting a restricted quantity of air to said vaporizer, whereby to retard the accumulation of carbonaceous fuel residue on said vaporizing surface during the time intervals when fuel is being supplied thereto and to cause said air to burn away from said vaporizing surface during an inactive time interval in which fuel is not supplied to the vaporizer such carbonaceous fuel residue as is formed during an active vaporizing time interval.

16. Apparatus for producing a continuous supply of fuel vapor from liquid hydrocarbon fuel including structure forming different vaporizing chambers each having a vaporizing surface, fuel feeding means for supplying a liquid hydrocarbon fuel alternatively to different ones of said vaporizing surfaces, means for continuously admitting to each of said vaporizing chambers a quantity of air sufficient to retard by combustion the accumulation of carbonaceous fuel residue on the vaporizing surface therein but insufficient to form in the chamber a combustible mixture with

the gaseous hydrocarbon fuel vaporized therein and means for continuously withdrawing gaseous fluid from each of said vaporizing chambers.

17. Apparatus for producing heat comprising a gaseous fuel burner, a plurality of liquid fuel vaporizers each arranged to be heated continuously by heat from said burner, means for feeding a liquid hydrocarbon fuel alternatively to different ones of said vaporizers to form fuel vapor therein, conduit means extending from said burner to said vaporizers to cause draft created by the burner to draw from said vaporizers the fuel vapor formed therein, and openings for continuously admitting a restricted quantity of air into each of said vaporizers, whereby to retard by combustion the accumulation of carbonaceous fuel residue in an active vaporizer to which fuel is being supplied and to burn away such residue in an inactive fuel vaporizer to which fuel is not being supplied.

18. Apparatus for producing heat comprising a gaseous fuel burner, a plurality of liquid fuel vaporizers arranged to be continuously heated by heat from said burner, conduit means extending from said burner to said vaporizers to cause draft created by said burner to continuously draw through each of said vaporizers a quantity of air insufficient to form a combustible gas mixture in any of said vaporizers with fuel vapor formed therein, and means for feeding liquid hydrocarbon fuel alternatively to different ones of said vaporizers to form fuel vapor therein, said conduit means including passages for flow to the burner of the fuel vapor formed in any active vaporizer to which fuel is supplied.

19. Liquid fuel combustion apparatus comprising a burner, a plurality of vaporizers for vaporizing liquid fuel for combustion in said burner, means including fuel conduits and fuel flow controlling apparatus for supplying liquid fuel alternatively to different ones of said vaporizers and means for continuously admitting a combustion supporting gaseous medium to each of said vaporizers whereby to burn away accumulated carbonaceous fuel residue in said vaporizers during periods of non-supply of liquid fuel thereto.

GUSTAF DALEN.
